GERRIT VAN DER HOEVEN, OF PARIS, FRANCE, ASSIGNOR TO RADIO CORPORATION OF AMERICA, A CORPORATION OF DELAWARE

APPARATUS FOR EXHAUSTING TUBES

Application filed October 26, 1927, Serial No. 228,751, and in the Netherlands October 29, 1926.

This invention is connected with apparatus for exciting a high frequency current in a coil mounted on a rotary body.

According to the invention power is supplied by an inductive coupling, the secondaries of which are adapted to rotate with the rotary body whereas the primaries through which passes a high frequency current are stationary.

10 This apparatus has a wide range of employment in the radio industry in which the electrodes of discharge tubes are generally deprived of occluded gases by means of high frequency current. For this purpose a machine according to the invention may be constructed comprising heads for the said discharge tubes and high frequency coils mounted on a rotary carrier, the high frequency coils being energized in the manner above indicated. The said coils are connected in an oscillation circuit formed by a condenser mounted on the carrier and secondary windings mounted coaxially to the axis of rotation of the carrier. Said windings being 15 surrounded by stationary primary windings the advantage is obtained that the coils can be supplied with a high frequency current in any position of the carrier.

According to the invention the heads for 20 the discharge tubes are adapted to move relatively to the high frequency coils, the advantage being thus obtained that the latter can be rigidly secured to the carrier. According to one embodiment of the invention 25 the apparatus is combined with a device for exhausting discharge tubes. The heads are provided with a locking device which can be caused to communicate with the exhausting pumps so that it is possible to effect 30 simultaneously the exhaustion of the discharge tubes and the gas extracting operation by means of high frequency current. Thus the advantage is ensured that the lamps 35 can be readily exhausted and are at the same time deprived of any residual gases produced as a result of the gas extracting operation by means of the high frequency current. The drawing illustrates one embodiment of the 40 invention.

In the said drawing:

Figure 1 is a view, partially in section, of an exhausting device in which high frequency coils rotate with the rotary carrier.

55 Figure 2 is a diagram showing the manner in which the said coils are energized.

Referring to Figure 1 a shaft 1 has rigidly secured to it sleeves 2 and 3 and is intermittently actuated by a source of energy (not shown). Said shaft has also secured to 60 it a valve member 4 which registers with a stationary body 5 adapted by means of a bore 6 and a conduit 7 to connect an exhausting pump (not shown) to a bore 8 of the valve member 4. The said bores are connected by means of flexible conduits 9 to obturating devices 10 in heads 11 which by means of levers 12 are pivoted to the sleeve 2. The said levers 12 carry rollers 13 which ride on a stationary cam-track 14.

70 The sleeve 2 has mounted on it by means of supports 15 coils 16 which consequently are moved when the shaft 1 is actuated. The sleeve 3 has mounted on it a condenser 17 and rods 18 which support a plate 19. This plate 19 has secured to it a frame 22 which has wound on it windings 23 secured to a support 24 which is stationary by means of rods 25.

75 The manner in which the coils 16 are energized is diagrammatically shown in Figure 2. In this figure a high frequency current passes through windings 23, the number 21 indicating windings which constitute with the condenser 17 an oscillation circuit 80 with which the high frequency coils 16 are connected in series.

85 The operation of the machine is as follows:

The operator inserts a discharge tube by 90 means of its exhausting tube in the obturating device in position A. As the shaft 1 is rotated the next lever 12 together with its obturating device will occupy the position A while the first mentioned discharge tube will 95 be carried along with the carrier. As the roller 13 rides on the raised edge of the cam track 14 the discharge tube will be slipped into the coil 16. The high frequency current which will be produced by the inductive ac- 100

tion of the windings 23 and 21 in the oscillation circuit 21, 17, 16 will constantly pass through the said coils. By reason of the said high frequency current the electrodes of discharge tubes will be deprived of occluded gases while the exhausting operation is being carried on, thus driving off the residual gases.

What I claim is:

- 10 1. A device for exhausting evacuated tubes, comprising a coil designed to carry high frequency electrical oscillations, means for carrying the tube within the field of the high frequency oscillations, and an automatic valve connecting the tube to an exhausting means when the tube is in the field of the high frequency oscillations.
- 20 2. A device for exhausting evacuated tubes, comprising a coil designed to carry high frequency oscillations, a rotatable frame, supports for tubes carried by said frame, means to rotate said frame thereby carrying the tubes within the field of the high frequency oscillations of the coil, and a valve connecting the supports with an exhausting means when the tube is in the field of the high frequency oscillations.
- 30 3. A device for exhausting evacuated tubes, comprising a coil designed to carry high frequency oscillations, a rotatable frame, a plurality of arms mounted on said frame, supports for tubes carried by said arms, means to rotate said frame thereby carrying the tubes within the field of the high frequency oscillations of the coil, and a valve connecting the supports with an exhausting means when the tube is in the field of the high frequency oscillations.
- 40 4. A device for exhausting evacuated tubes, comprising a coil designed to carry high frequency oscillations, a rotatable frame, arms pivotally mounted upon said frame, supports for tubes carried by said arms, a stationary cam engaging the said arms, said cam positioning the tubes within the field of the high frequency oscillations and removing them therefrom as the frame rotates, and a valve connecting the supports with an exhausting means.
- 50 5. A device for exhausting evacuated tubes, comprising a coil designed to carry high frequency oscillations, a rotatable frame, arms pivotally mounted upon said frame, supports for tubes carried by said arms, a stationary cam engaging the said arms, said cam positioning the tubes within the field of the high frequency oscillations and removing them therefrom as the frame rotates, a stationary valve member, and a rotatable valve member fixed to rotate with the frame to connect the exhausting means with the support and tube when the tube is positioned in the high frequency oscillating field.
- 60 6. A device for exhausting evacuated tubes, comprising a rotatable frame, a secondary

coil mounted on said frame, a condenser connected in series with the secondary coil mounted on said frame, a plurality of coils connected in series with one another and with the said condenser and secondary coil mounted on said frame, a plurality of pivoted arms on said frame, supports for tubes on the arms, a stationary cam engaging said arms and causing the tubes on the supports to be inserted within a coil and removed therefrom as the frame rotates, a valve automatically connecting the supports with an exhausting means when the tubes are within the coils, and a primary coil surrounding said secondary coil and designed to carry a high frequency oscillating current.

7. A device for exhausting evacuated tubes, comprising a rotatable frame, a high frequency oscillating circuit mounted on said frame including a plurality of coils, supports for tubes on said frame, means to bring the tubes within the field of the coils, and a valve connecting the tubes with an exhausting means during the time the tube is subject to the high frequency oscillating field of the coil.

8. A device for exhausting evacuated tubes, comprising a rotatable frame, a high frequency oscillating circuit mounted on said frame including a plurality of coils, a secondary coil in series with said oscillation circuit mounted on said frame, a stationary primary coil surrounding the secondary coil, supports for tubes on said frame, means to bring the tubes within the field of the coils, and a valve connecting the tubes with an exhausting means during the time the tube is subject to the high frequency oscillating field of the coil.

9. A device for exhausting evacuated tubes, comprising a rotatable frame, a high frequency oscillating circuit mounted on said frame including a plurality of coils, supports for tubes on said frame, a cam adapted to bring the tubes within the field of the coils, and a valve connecting the tubes with an exhausting means during the time the tube is subject to the high frequency oscillating field of the coil.

10. A device for exhausting tubes, comprising a rotatable frame, means on said frame for producing high frequency oscillations, stationary means for energizing the means on the frame, stationary exhausting means, means rotatable with the frame for inserting the tube into the field of the high frequency oscillating means, and means for automatically connecting the tube with the exhausting means as the tube is heated by the high frequency field.
